UNITED STATES PATENT OFFICE.

FRANCISSEK AUFINGER AND JOSEFF LEMANKIEWICK, OF BRADDOCK, PENNSYLVANIA.

LIFE-BOAT.

1,142,224.

Specification of Letters Patent.

Patented June 8, 1915.

Application filed July 31, 1914. Serial No. 854,418.

To all whom it may concern:

Be it known that we, FRANCISSEK AU-
FINGER and JOSEFF LEMANKIEWICK, sub-
jects of the Emperor of Russia, residing at
Braddock, in the county of Allegheny and
State of Pennsylvania, have invented cer-
tain new and useful Improvements in Life-
Boats, of which the following is a specifica-
tion, reference being had therein to the ac-
companying drawing.

This invention relates to life boats and has
for its object to provide a boat of such class,
in a manner as hereinafter set forth, having
a closed hull and further having means in a
manner as hereinafter set forth, for propelling
the boat as well as ventilating the hull.

Further objects of the invention are to
provide a life boat which is comparatively
simple in its construction and arrangement,
strong, durable, efficient and convenient in
its use, and comparatively inexpensive.

With the foregoing and other objects in
view the invention consists of the novel con-
struction, combination and arrangement of
parts as hereinafter more specifically de-
scribed and illustrated in the accompanying
drawings wherein is shown an embodiment
of the invention, but it is to be understood
that changes, variations and modifications
can be resorted to which come within the
scope of the claims hereunto appended.

The drawing illustrates partly in section
and partly in elevation a life boat in accord-
ance with this invention.

Referring to the drawing the hull of the
boat is formed with a lower section 1, and an
upper section 2, each substantially elliptical
in plan. The stern of the hull is flat as at
3 and hinged to said flattened portion as at
4, is a rudder 5, the latter having its upper
end provided with a lateral extension 6,
which projects into the hull and is connected
with any suitable means, not shown, for the
purpose of turning the rudder when desired.

Arranged below the rudder 5 is a propeller
7, which is carried by a propeller shaft 8,
the latter extending into the section 1 of the
hull, above the lower deck 9. The propeller
shaft 8 is connected with any suitable drive
mechanism, not shown.

Arranged within the hull is a superposed
series of decks, 10, 11, 12, 13, 14, 15 and 16,
and arranged within the hull at the bow, as
well as at the stern thereof, is a superposed
series of end decks as indicated at 17, 18, 19,
20, 21, 22 and 23. The arrangement of the

end decks at the bow is the same as illus-
trated at the stern.

Vertically disposed spaced partitions are
arranged within the hull, as indicated at 24, 60
25, 26 and 27. The partitions 24 and 26 are
arranged at the ends of the intermediate
decks and the partitions 25 and 27 are ar-
ranged at the inner ends of the end decks.
The partition 24 is spaced from the parti- 65
tion 25 to provide a chamber 28 and the
partition 26 is spaced from the partition 27
to provide a chamber 29.

Arranged at the bow are a pair of cowls
30, only one of which is shown. The cowls 70
30 are enlargements to and formed on the
stems 31 extending down into the chamber
29. Arranged at the stern is a pair of cowls
32, only one of which is shown, and which
are enlargements, to the stems 33 of the 75
cowls 32 extending down into the chamber
28. Projecting laterally from the stem 31
of the cowls 30 and from the stems 33 of
the cowls 32 and projecting between the
decks 10 to 16 inclusive and between the 80
decks 9 and 16 are ventilating pipes 34.

That portion of the hull below the deck 9
forms a water reservoir 35, and extending
down into said reservoir 35, is a water feed
pipe, connecting with a pump, not shown, 85
and leading from the pump are water sup-
ply pipes 37, 38 from the decks 9, and
11 to 16.

A stair way 39 associates with the decks
9, and 11 to 16. 90

Any suitable means may be employed so
that access may be had to the decks 18 to 23.

Section 2 of the hull is provided with
windows 39 and doors 40. At the top of the
section 2 of the hull a signaling device, such
as an electric lamp, which is indicated at 41,
is provided.

What we claim is:

1. A life boat comprising a hull formed
of two hollow substantially semi-elliptical 100
sections secured together to provide inclo-
sures, a plurality of vertical and horizontal
partitions arranged therein to provide super-
posed decks therein, certain of the vertical
partitions being spaced apart to provide 105
chambers therebetween, a plurality of hol-
low stems arranged in said chambers and
projecting through the upper section of said
hull, the extreme upper ends thereof being
enlarged and designed to form cowls, and a 110
plurality of ventilating pipes formed on
said stems and projecting laterally there-

from to points between certain of the horizontal partitions forming decks, and means for the propulsion of said hull.

2. A life boat comprising a hull formed of a pair of hollow semi-oval sections secured together to provide an inclosure therein, a plurality of vertical and horizontal partitions arranged in the inclosure to provide intermediate and end decks superposed one upon the other, the vertical partitions being spaced one from the other to provide chambers, a plurality of hollow stems arranged in said chambers and projecting above the upper section of said hull, the extreme upper ends of said stems being en-

larged and bent to form cowls, a plurality of laterally extending ventilating pipes carried on the stems and projecting between the intermediate decks, said ventilating pipes projecting through the adjacent vertical partitions, whereby to support said stems in position in the chambers, and means for the propulsion of said hull. 20

In testimony whereof we affix our signatures in the presence of two witnesses.

FRANCISSEK AUFINGER.
JOSEPF LEMANKIEWICK.
